DECANTER

Ernest L. Du Pree, New York, N.Y., assignor to Schenley
Industries, Inc., New York, N.Y., a corporation of
Delaware

Filed Sept. 13, 1963, Ser. No. 76,583

Term of patent 14 years

(Cl. D58—6)

FIG 1

FIG 2

FIG 3

FIG 4

FIG 5

FIG 6

FIGURE 1 is a front perspective view of a decanter embodying my new design;

FIGURE 2 is a rear elevational view thereof on a reduced scale with the closure removed;

FIGURE 3 is a bottom plan view thereof;

FIGURE 4 is a vertical sectional view, as seen on the line 4—4 of FIGURE 2, looking in the direction of the arrows;

FIGURE 5 is a horizontal sectional view, as seen on the line 5—5 of FIGURE 2, looking in the direction of the arrows; and

FIGURE 6 is a horizontal sectional view, as seen on the line 6—6 of FIGURE 1, looking in the direction of the arrows.

The side of the decanter not shown is substantially the same as the side of the decanter shown and the portion of

the decanter closure not shown is substantially the same as the corresponding parts of the closure shown.

I claim:

The ornamental design for a decanter, as shown and described.
